UNITED STATES PATENT OFFICE.

ROBERT V. CHEATHAM, OF ST. MATTHEWS, KENTUCKY.

CIRCUIT-CLOSER FOR TROLLEY SIGNAL SYSTEMS.

1,136,314.

Specification of Letters Patent. Patented Apr. 20, 1915.

Application filed June 4, 1912. Serial No. 701,677.

To all whom it may concern:

Be it known that I, ROBERT V. CHEATHAM, a citizen of the United States, and a resident of St. Matthews, county of Jefferson, and State of Kentucky, have invented 5 a new and useful Improvement in Circuit-Closers for Trolley Signal Systems, of which the following is a specification.

The object of my invention is to provide 10 a device of this class which may be attached to a trolley wire, and which, when in use, will close and open an electric circuit for a signal or other system when a trolley wheel approaches the device from one direction, 15 but will not close the circuit when the trolley wheel approaches from the other direction. This object is accomplished by my invention, one embodiment of which is hereinafter more particularly set forth.

20 For a more particular description of my invention, reference is to be had to the accompanying drawing, forming a part hereof, in which—

25 Figure 1 is a perspective view of a device embodying my invention. Fig. 2 is a plan view of the same. Fig. 3 is an end elevation of the same. Fig. 4 is a sectional view, taken on the line 4—4 of Fig. 3, looking in the direction of the arrows. Fig. 5 is a 30 similar view to Fig. 4, except that some parts are shown in different positions.

Throughout the various views of the drawings, similar reference characters designate similar parts.

35 An ordinary post 1 supports a board 2 in any suitable manner, and this post is preferably placed between the span wires 19 and 20 of an ordinary trolley wire 16. The board 2 has mounted thereon a suitable pin 40 7 on which is mounted an insulated disk 13 which is pivoted so as to oscillate on said pin 7. The disk 13 has a recess 10 the ends of which are adapted to engage a pin 11 projecting from the board 2. This disk 13 also 45 carries a suitable counterweight 12 which is fixed thereon and adapted to keep one end of the recess 10 in contact with the pin 11. The disk 13 also carries an arm 5 fixed thereto by screws 6, or other suitable means, two 50 screws being shown in the drawing, and this disk 13 also carries a second and pivoted arm 3 which is pivotally mounted at 4 on this disk, and the disk is provided with a projecting pin 23 which limits the movement of the arm 3 in one direction, and in the other direction its movement is limited

by the fixed arm 5 which is secured by screws 6. Both of these arms are electrical conductors, for a purpose that will appear below.

60 The arm 3 is connected to the trolley wire 16, or other suitable source of electrical supply, by means of a conductor 21 which has coils or other suitable means so as not to interfere with the movement of the arm 3. 65 Another wire or conductor 22 similarly made and disposed is connected to the arm 5 and runs to a signal or other device which is supplied with electricity through this apparatus. The conductor or wire 22 also has 70 coils or other suitable means so as not to interfere with the movement of the arm 5. The disk 13, which is of insulating material such as wood or fiber-board, is also provided with a pin 8 which projects therefrom at 75 some length, and this pin is adapted to be engaged by the upper end of an arm 9 pivotally mounted by a loose pivot on a pin 14 that extends from the board 2. The arm 9 has two parts. The upper one is vertically 80 disposed and adapted to engage the pin 8, as above described, and the lower one is horizontally disposed, the free end of which runs to an ear 15 fixed on the trolley wire 16. This ear 15, like the ears 17 and 18, is 85 rigidly mounted on the trolley wire 16. The ears 17 and 18 are connected to the span wires 20 and 19, as shown in the drawing, or in any other suitable way.

85 In view of the foregoing, the operation of 90 my improved device will be readily understood. Assuming that the trolley wheel approaches the apparatus from the ear 18, the trolley wheel will cause the upper end of the arm 9 to swing clockwise and engage the pin 95 8 and force the disk 13 to rotate so as to elevate the weight 12 and cause the arm 3 to be lowered so it is within reach of the upper end of the arm 9 when it reverses its direction of movement as it does, as soon 100 as the trolley wheel leaves the ear 15. As compared with the movement of the upper end of the arm 9, the movement of the disk 13 is slow so that the upper end of the arm 9 has time to engage the lower end of the 105 arm 3 and throw the same so that it momentarily engages the arm 5, which is fixed to the disk and thereby closes the circuit. The arm 3 is held against the arm 5 until the trolley wheel gets far enough from the ear 110 15 to allow the arm 9 to resume its normal position, or nearly resume its normal posi-

tion, and as soon as the arm 9 has shifted sufficiently, the arm 3 falls by gravity against the stop pin 23, thus opening the circuit abruptly and rapidly, and then the counter-weight 12 acts so as to bring the disk back to its original position. When the trolley wheel approaches from the ear 17 the first movement of the arm 9, is anti-clockwise which is in an inoperative direction, so that no movement of the disk 13 results from this movement of the arm 9, and when the arm 9 is swung in the opposite direction that is, clockwise, as it is when the trolley wheel leaves the ear 15 the upper end of the arm 9 engages the pin 8 and then rotates the disk 13, but when the trolley wheel gets further away the arm 9 returns to its normal position without engaging the lower end of the arm 3, so that no circuit is closed between the arms 3 and 5.

While I have shown and described one embodiment of my invention, it is obvious that it is not restricted thereto, but is broad enough to cover all structures that come within the scope of the annexed claims.

Having thus described my invention, what I claim is,

1. In a device of the class described, a trolley wire, an ear, an arm connected to this ear and fixed to said trolley wire, means for pivotally mounting the same, an electric circuit and means operated by said arm for closing and opening said electric circuit when a trolley wheel passes in one direction and not closing the said circuit when a trolley wheel passes in the other direction.

2. In a device of the class described, a trolley wire, an ear, an arm connected to this ear secured to said trolley wire, and means for pivotally mounting the same with a loose pivot, an electric circuit and means operated by said arm for closing and opening said electric circuit when a trolley wheel passes in one direction and not closing the said circuit when a trolley wheel passes in the other direction.

3. In a device of the class described, a trolley

wire, an arm connected to said trolley wire and means for pivotally mounting the same, an oscillating member mounted on a pivot means on said oscillating member for causing same to be oscillated by said arm in one direction only, an electric circuit and means on said oscillating member operated by said arm for closing said electric circuit when a trolley wheel passes in one direction.

4. In a device of the class described, a trolley wire, an arm connected to said trolley wire and means for pivotally mounting the same, an oscillating member and means for mounting the same so that it can oscillate, a pin on said oscillating member adapted to be engaged by said arm, an arm fixed to said oscillating member, an arm pivotally mounted on said oscillating member, and an electric circuit adapted to be closed by the action of the arm on the pin on said oscillating member when a trolley wheel passes in one direction.

5. In a device of the class described, a trolley wire, an arm connected to said trolley wire and means for pivotally mounting the same, an oscillating member and means for pivotally mounting the same, a counter-weight carried by said oscillating member and means for limiting the movement of the oscillating member on its pivot, a pin extending from said oscillating member and adapted to be connected by said arm, a second arm fixed to said oscillating member and adapted to be connected to one part of an electric circuit, a third arm pivotally mounted on said oscillating member and means for connecting the same to another part of an electric circuit so that the last mentioned arm may be thrown when the oscillating member is turned in one direction by the first mentioned arm to close an electric circuit through the second mentioned arm.

ROBERT V. CHEATHAM.
